US0D1017931S

(12) **United States Design Patent** (10) **Patent No.:** **US D1,017,931 S**
(45) **Date of Patent:** **** Mar. 12, 2024**

(54) **APPLIANCE DOOR**

(71) Applicant: **WHIRLPOOL CORPORATION**,
Benton Harbor, MI (US)

(72) Inventors: **Jonathan D. Pugh**, Benton Harbor, MI
(US); **John Michael DeBoer**, St.
Joseph, MI (US); **Ameresh B.**
Viswanathan, St. Joseph, MI (US);
Russikant Behera, Punke (IN); **Darryl**
C. Bodine, St. Joseph, MI (US)

(73) Assignee: **Whirlpool Corporation**, Benton
Harbor, MI (US)

(**) Term: **15 Years**

(21) Appl. No.: **29/814,183**

(22) Filed: **Nov. 4, 2021**

Related U.S. Application Data

(63) Continuation of application No. 29/726,288, filed on
Mar. 2, 2020, now Pat. No. Des. 938,109.

CLAIM

The ornamental design for an appliance door, as shown and described.

DESCRIPTION

FIG. 1 is a top, front perspective view of an appliance door showing our new design;

FIG. 2 is a front view of the appliance door of FIG. 1;

FIG. 3 is right side view of the appliance door of FIG. 1;

FIG. 4 is a left side view of the appliance door of FIG. 1; and,

FIG. 5 is a top view of the appliance door of FIG. 1.

Portions of the drawings shown in broken lines form no part of the claimed design.

1 Claim, 5 Drawing Sheets
